ROLLER SKATE

Albert Wintercorn, Columbus, Ohio

Application May 9, 1950, Serial No. 160,963

6 Claims. (Cl. 280—11.28)

1

The present invention relates to roller skates, and has particular reference to roller skates in which are embodied flexibly joined and resiliently movable wheel-carrying trucks.

An object of the invention is to provide a roller skate in which a foot-attaching base plate is resiliently supported by wheeled trucks forming component parts of the skate.

A further object of the invention is to provide a roller skate in which a foot-attaching base plate is resiliently supported by truck assemblies of the skate, and wherein provision is made for enabling the base plate to rock laterally of the skate about a substantially horizontal axis, thus enabling a skater to negotiate turns and inclined skating surfaces more skillfully and with better balance than heretofore.

It is another object of the invention to provide a roller skate having a pair of front wheels supported for bodily turning movement about a vertical axis, and wherein provision is made for imparting controlled turning movement to said wheels about said axis in a manner proportionate to the degree of lateral tilting movement of a foot-supporting base plate of the skate.

A further object of the invention is to provide a skate having front and rear truck assemblies arranged in longitudinally aligned and relatively spaced order and wherein said assemblies are united by a contractile coil spring.

For a further and more detailed understanding of the present invention, including various other objects and advantages realized therefrom, reference is made to the following description and the accompanying drawings, wherein:

Fig. 1 is a view in side elevation of a roller skate constructed in accordance with the present invention;

Fig. 2 is a horizontal sectional view taken through the roller skate on the plane indicated by the line 2—2 of Fig. 1;

Fig. 3 is a vertical longitudinal sectional view taken through the skate on the plane disclosed by the line 3—3 of Fig. 2;

Fig. 4 is a horizontal sectional view taken through the front truck of the skate on the plane indicated by the line 4—4 of Fig. 3;

Fig. 5 is a similar view taken through the rear truck of the skate on the line 5—5 of Fig. 3;

Fig. 6 is a vertical transverse sectional view taken through the front truck of the skate on the plane indicated by the line 6—6 of Fig. 1, and showing the oscillatory base plate support of the front truck in its normal upright position;

Fig. 7 is a similar view disclosing the oscillatory

2

support in a tilted position, and illustrating the action thereof in turning the front wheels of the truck about a vertical axis;

Fig. 8 is a detail horizontal sectional view taken on the plane indicated by the line 8—8 of Fig. 1, and disclosing more particularly the bottom construction of the front truck;

Fig. 9 is a detail view of the needle bearings for the truck wheels.

10 In accordance with the present invention, I provide a skate embodying front and rear longitudinally aligned and relatively spaced wheel-carrying truck assemblies, each of said assemblies including a horizontally disposed fulcrum upon which 15 is mounted for rocking movement in a vertical plane, transversely of the skate, a tiltable foot plate supporting member, the latter being formed to include a body and a headed shank on which is slidably positioned a retaining cup carried by 20 the under side of the foot-attaching base plate of the skate, a coil spring being disposed around the shank of the tiltable member and confined between a shoulder provided on the body of said member and a seat on said cup, whereby to provide for resilient movement of the truck assembly 25 relative to the base plate of the skate.

Also, the invention provides a roller skate in which a front truck assembly is present which is formed to enable the foot-receiving base plate of the skate to yield vertically in response to spring-supporting means in absorbing shock and jar imparted in use to the skate and, further, rock laterally, the truck including a body or bolster member to the forward portion of which is pivotally connected for turning movement about a vertical axis a wheel-carrying frame bracket, the latter embodying a horizontally disposed slotted extension in which the lower end of a tiltable plate-supporting member is mounted for oscillatory movement on the body member, the arrangement being such that rocking movement of the tiltable member about a horizontal axis is utilized in adapting the skate more readily to turning movements and effecting automatically bodily turning movement on the part of the wheel-carrying bracket of said front truck assembly, thus enabling the front wheels of the skate to turn in parallelism about a common vertical axis when lateral tilting movement of the foot-supporting plate of the skate is produced.

Referring to the drawings, my improved roller skate construction embodies a foot-supporting base plate 1 to which the foot or shoe 2 of the skater is adapted to be attached in any conventional manner, such as by the use of screws or

the like. The base plate is supported by means of front and rear trucks which are indicated in their entireties by the numerals 3 and 4, respectively.

The front truck is formed to include a bolster body 5 which is vertically slotted, as at 6, for the reception of a pivotally mounted plate-supporting member 7. The latter includes a body 8 which is longitudinally bored as at 9 to receive the intermediate portion of a shaft 10, the end portions of said shaft being disposed for turning movement in a socket and an opening 11 provided longitudinally in the bolster body 5 in registry with the bore 9 of the supporting member 7. The body 8 is formed with a threaded opening for the reception of a set screw 12, which bears on the shaft 10 to cause the latter to turn in unison with the member 7.

The forward part of the bolster body 5 is formed with an integral, forwardly projecting and horizontally disposed shelf 13, which is provided centrally with a vertical opening 14. The shelf 13 is positioned in a recess 15 provided in the rear of a wheel-carrying frame bracket 16. This bracket comprises a vertically disposed and transversely extending plate-like body 17 which is provided with vertical slots 18 for the reception of the forward pair of supporting wheels 19 of the skate. At its front, the plate-like body is formed with integral forwardly projecting spaced ears 20 which, as shown in Fig. 9, are provided with horizontally disposed and aligned threaded openings for the reception of adjustable externally threaded bearing studs 21.

The outer ends of these studs are socketed as at 22 for the reception of the shanks of rotating tools, not shown, while the inner ends of said studs are formed with tapered sockets for the reception of the outer conical ends 23 of wheel axles 24. Each of these axles has a threaded body 25, which is received in threaded openings provided in a pair of metallic disks 26 disposed in circular recesses 27 provided in the inner and outer faces of the wheels 19, the disks being held in place by the screws indicated at 28, the shanks of the latter penetrating the wooden or other bodies of the wheels 19. Set screws 29 may be used for maintaining the adjustment of the anti-friction axle-receiving studs 21. By the use of this construction, the wheels of the front truck are supported so that the same may rotate freely about a common horizontal axis, and in a secure and substantial manner.

The rear part of the body plate 17 of the front truck has integrally formed therewith a horizontally projecting lip 30 which rests upon the upper surface of the shelf 13 of the bolster body, the lip 30 being formed with an opening for the reception of a vertical king bolt 31, the threaded lower end of said bolt being received in a registering opening 32 formed in a horizontally disposed bracket extension 33 which underlies the bolster body 5. At its rear, the extension 33 includes an arcuate slot 34 in which is positioned the lower end of a headed stud 35 which is stationarily carried by and projects downwardly from the rear of the bolster body 5, thereby adding support to the pivotally movable frame bracket 16.

The extension 33 of said bracket, in front of the arcuate slot 34, is longitudinally slotted as at 36 to receive the spherically headed lower end of the supporting member 7, the spherical head of said member being indicated at 37. In this instance, the latter is confined between a pair 75

of adjustable plates 38 which are carried by the screws shown at 39 in Fig. 8, the said screws being arranged in bars 40 stationarily carried by and depending from the under surface of the extension 33 at the sides thereof. When the foot plate 1 of the skate is rocked, corresponding rocking or tilting movement in a lateral direction is imparted to the member 7. Since this member is carried by the shaft 10 arranged intermediately of the height of the member 7, the lower spherical end of said member imparts turning movement to the extension 33 about the axis afforded by the king bolt 31, causing turning movement of the ground-engaging wheels 19 about the axis of the king bolt to an extent proportionate to the degree of lateral tilting movement of the foot plate 1, as depicted in Figs. 6 and 7 of the drawings.

Yieldable restraint of the supporting member 7 in its vertical or two laterally tilted positions is obtained by providing the front and rear surfaces of the body 8 of said supporting member with spherical depressions 41 which are adapted to receive the end portions of spring-pressed balls 42 mounted in aligned bores 43 provided in the bolster body 5. The balls 42 are spring-pressed into engagement with the depressions 41 by means of springs 44 which may be tensioned by the screws indicated at 45, the latter being threaded into the outer ends of the bores 43. The spring-pressed balls 42 thus serve to yieldably retain the foot plate in its various positions of rocking movement about the axis provided by the shaft 10, to aid the skater when rounding curves and banking toward the inside of the curve.

The body 8 of the supporting member 7 terminates upwardly in a shank 46 and above said shank in a head 47. The shank is received in an opening 48 provided in the lower wall 49 of a retaining cup 50. This cup has the upper portion thereof outwardly and horizontally flanged as at 51, the upper surface of said flange engaging with gaskets 52 through which pass the shanks of securing screws 53 employed in uniting the retaining cup 50 with the under surface of the base or foot plate 1, the lower ends of the screws 53 being equipped with tightening nuts 54, the latter serving to hold the securing cup in closely held engagement with the gaskets 52 and the foot plate 1.

The interior of the cup includes a chamber 55 in which the head 47 is positioned. A coil spring 56 surrounds the shank 46 and is disposed between a shoulder 57 formed on the bottom of the cup 50 and a complementary shoulder 58 provided at the upper end of the body 8 of the member 7, the spring serving to resiliently support the foot plate and the weight of the skater on the front truck. The degree of vertical movement of the foot plate relative to the headed upper end of the member 7 is regulated, as shown in Fig. 6, by providing the head 47 at its sides with slots 59 in which are received the reduced inner ends of a pair of set screws 60, the latter being threaded into openings provided in registration with each other in the cup 50.

The rear truck 4 of each skate of the present invention is formed to comprise a frame 61 having a transverse plate 62 which corresponds in formation to the plate 17 of the frame 16, the plate 62 being formed with rearwardly projecting ears 63 for the rotatable reception of a rear pair of wheels 64, which are supported for rotation

in connection with said plate and its ears 63 as are the front wheels 19 in connection with the plate 17 and ears 20, utilizing the same anti-friction supporting devices depicted in Fig. 9.

To mount the rear portion of the foot plate 1 on the rear frame 61, use is made of the retaining cups 65 which correspond with the cups 50 in construction and function, the cups 65 being attached to the under side of the plate 1 by the fastening devices shown at 66 which are the same as those disclosed at 52, 53 and 54 and previously described in connection with the front truck of the skate. In fact, the only fundamental difference between the front and rear truck assemblies of the present invention resides in the fact that the rear truck and its wheels 64 do not turn about a vertical axis, as do the front wheels about the king bolt 31. Thus the plate 62 includes a forwardly projecting horizontally disposed shelf 67. The shelf is formed with an opening for the reception of the lower end 68 of an upright ear 69, the latter being formed with a horizontal opening 70 for the reception of the intermediate portion of a shaft 71, which is longitudinally aligned with the shaft 10, the shaft 71 being retained in the opening 70 by a set screw 72. Rockable on the shaft 71 is the bifurcated lower end 73 of a laterally tiltable base plate supporting member 74 which corresponds in function to the forward member 7, a shock absorbing coil spring 75 being interposed between the end 73 of the member 74 and the retaining cup 65.

Spring-pressed ball devices 76, corresponding with the ball devices 42 of the forward truck assembly, engage with spherical depressions 77 provided in the forward face of the bifurcated lower end 73 of the member 74. The devices 76 coact with the devices 42 for the purpose of yieldably holding the foot or base plate 1 in various positions of rocking adjustment about the horizontal axes afforded by the shafts 10 and 71. The adjoining ends of the shafts 10 and 71 are united by a coil-type contractile spring 78, which serves to resiliently unite the front and rear truck assemblies.

In view of the foregoing, it will be seen that the present invention provides improved roller skates which respond sensitively to the movements of the skater's feet in controlling the operation of the skates and the directions of movement which they follow over a rink surface or other supporting base. The user of the skates by laterally tilting the attaching plates will rock the supporting members, indicated at 7 and 74, on the front and rear truck assemblies, the movement being utilized to retain the balance of the skater when negotiating turns and the like and also to enable the front pair of wheels on each skate to deflect angularly with respect to the longitudinal axes of the skates in facilitating quickly executed turns. It will be noted that the horizontal axis of the front steerable wheels 19 is disposed in advance of the vertical axis of turning movement of their supporting bracket on the lip or bench 13 of each forward truck. This construction enables the foot-attaching plate 1 to be disposed at a normal or average height above the rink surface and to also utilize the vertical shock-absorbing spring means 56 and 75. By placing the forward pair of wheels 19 in the advanced position illustrated, the skates are provided with improved stability and balance, rendering the same easy to use and control.

Virtually all the parts are formed from light-weight metals such as aluminum and its alloys,

so that the skate is surprisingly light in weight when its construction is taken into consideration.

I claim:

1. In roller skate construction, a truck assembly comprising a body member, a bracket, a pair of spaced wheels carried by said bracket for turning movement about a horizontal axis, means pivotally connecting said bracket with said body member for pivotal movement about a vertical axis disposed substantially midway between said wheels and to the rear of said horizontal axis, said bracket including a rearwardly disposed extension arranged beneath said body member, an upright supporting member, a horizontally disposed pivotal connection uniting said supporting member substantially intermediately of the height thereof with said body member and adapting said supporting member for rocking movement in a confined vertical plane transversely of the truck assembly, said supporting member having a lower end received between closely adjacent side walls of a slot formed in the horizontal extension of said bracket, whereby to effect turning movement of said bracket about its vertical axis and the bodily shifting of the wheels carried thereby upon rocking movement of said supporting member, and a foot-attaching plate joined for support with the upper end of said supporting member.

2. In roller skate construction, a truck comprising a body member formed with a forwardly projecting bench and a relatively rearwardly disposed transversely extending vertical slot, a bracket, a pair of spaced base-engaging wheels carried by the ends of said bracket for turning movement about a substantially horizontal axis, means pivotally connecting said bracket with the bench of said body member for pivotal movement about a vertical axis disposed substantially midway between said wheels to the rear of their horizontal axis of turning movement, said bracket including an extension arranged beneath said body member, said extension being formed with a slot disposed in registration with the slot of said body member, an upright supporting member, a horizontal pivotal connection uniting said supporting member intermediately of the height thereof with the body member of said truck, said pivotal connection adapting said supporting member for transverse tilting movement in a substantially vertical plane, said supporting member having a lower end received between relatively closely positioned side walls of the slot formed in said bracket extension, whereby to effect turning movement of said bracket and the wheels carried thereby about its vertical axis on said truck, and a foot-attaching plate joined for support with the upper end of said supporting member and movable in unison with the lateral tilting movements of the latter.

3. Roller skate construction as specified in claim 2 and wherein the bracket extension is formed with an arcuate slot disposed concentrically with respect to the vertical axis of turning movement of said bracket on said truck, and a stud projection carried by the body member of said truck, said projection being positioned in said arcuate slot.

4. Roller skate construction as defined in claim 2, and wherein the slot in the horizontal extension of said bracket is provided with relatively adjustable side wall forming plates for engagement with the lower end of said transversely tiltable supporting member, and threaded devices carried by the body member of said truck for

securing and maintaining the adjustment of said plates.

5. Roller skate construction as defined in claim 2, and wherein the laterally tiltable plate-supporting member is formed within the slot of the body member of said truck with opposed flat surfaces, at least one of said surfaces being provided with a plurality of spaced depressions disposed in arcuate order about the horizontal axis of tilting movement of the supporting member, and a spring-pressed ball device carried by the body member of said truck and engageable with said depressions to yieldably retain said supporting member in its laterally tilted positions.

6. In roller skate construction, a foot-attaching plate, front and rear longitudinally aligned wheel-carrying trucks arranged beneath said plate, means carried by said trucks supporting said plate for lateral tilting movement relative to said trucks, a bracket on said front truck carrying a forward pair of wheels, means pivotally connecting said bracket with said front truck, said means providing for turning movement of said bracket and the wheels carried thereby about a substantially vertical axis disposed to the rear and midway of the horizontal axis of turning movement of said forward pair of wheels, means

15

5 spaced and aligned cup devices rigidly attached to and depending from the under side of said plate, said cup devices being each formed with an internal chamber and a reduced axially disposed opening for the reception of the upper ends 10 of the lateral tilting supporting means of said trucks, and resilient means interposed between said lateral tilting means and said cup devices.

ALBERT WINTERCORN.

responsive to lateral tilting movement of said plate and the truck-carried supported means to impart turning movement to said bracket and its wheels about said vertical axis, longitudinally spaced and aligned cup devices rigidly attached to and depending from the under side of said plate, said cup devices being each formed with an internal chamber and a reduced axially disposed opening for the reception of the upper ends of the lateral tilting supporting means of said trucks, and resilient means interposed between said lateral tilting means and said cup devices.
